V. CAMPOS.

DIVER'S SUIT.

APPLICATION FILED JULY 17, 1919. RENEWED MAR. 21, 1922.

1,414,174.

Patented Apr. 25, 1922.

UNITED STATES PATENT OFFICE.

VICTOR CAMPOS, OF NEW YORK, N. Y.

DIVER'S SUIT.

1,414,174.

Specification of Letters Patent. Patented Apr. 25, 1922.

Application filed July 17, 1919, Serial No. 311,419. Renewed March 21, 1922. Serial No. 545,601.

To all whom it may concern:

Be it known that I, VICTOR CAMPOS, a subject of the King of Spain, and a resident of the city of New York, borough of Manhattan, in the county and State of New York, have invented a new and Improved Diver's Suit, of which the following is a full, clear, and exact description.

The object of the invention is to provide a new and improved diver's suit arranged to relieve the diver of pressure and to allow the diver to descend to a considerable depth. Another object is to prevent leakage at the joints even when the suit is subjected to heavy pressure on the diver descending to a considerable depth. Another object is to enable the diver to readily move the arms and legs and to do submarine work to practically any depth.

With these and other objects in view, the invention consists of certain novel features of construction as hereinafter shown and described, and then specifically pointed out in the claims.

A practical embodiment of the invention is represented in the accompanying drawings forming a part of this specification, in which similar characters of reference indicate corresponding parts in all the views.

Figure 1 is a front elevation of the diver's suit with one-half portion shown in section;

Figure 2 is an enlarged sectional plan view of one of the gripping devices, the section being on the line 2—2 of Figure 1; and

Figure 3 is an enlarged sectional elevation of one of the leak proof joints.

The diver's suit is made of a non-flexible pressure resisting material such as heavy sheet steel and the like, and the suit is adapted to wholly encase the diver so that the water pressure has no effect on the encased diver. The diver's suit in its general construction comprises a tubular body 10 on the top of which is detachably fastened a helmet 11 by bolts 12 or other fastening devices, and the said helmet 11 is provided with windows at the front and sides to enable the diver to look out. The lower portion of the body 10 is provided with angular joints 15 extending from the crotch 16 upwardly and outwardly and each of the said joints 15 is provided with an annular recess 17 adapted to be filled with a liquid, preferably an oil, or other suitable lubricant. Into this annular groove 17 extends an annular flange 18 formed on the

upper end of the corresponding thigh 19 of a tubular articulated leg 20 closed at its bottom by a foot-piece 21 adapted to contain the corresponding foot of the diver. Each annular flange 18 is provided with inner and outer packing rings 22 and 23 (see Figure 3) to form a leak-proof joint. It will be noticed that by this joint construction the pressure of the water against the thigh 19 is taken up by the oil or other liquid in the recess 17, that is, the flange 18 bears against the liquid thus allowing easy turning of the flange 18 in the recess 17. By the arrangement described the diver is enabled to impart a swinging movement to the thigh 19 even when submerged at a considerable depth, and without danger of binding of the parts at the joint. The other joints hereinafter referred to are similarly constructed for the same reasons. The flange 18 of each thigh 19 is engaged by a retaining ring 25 secured by bolts 26 to the body 10, the bolts also securing the corresponding joint 15 in place on the body.

The lower end of the thigh 19 is provided with a joint 30, similar to the joint 15, and engaged by an annular flange 31 formed on the upper end of the lower leg 32, the flange 31 being held in place by a retaining ring 33 screwed on the lower end of the thigh 19.

The lower portion of the lower leg 32 is in the form of a sleeve 35 screwed into the lower end of the lower leg 32, and on the lower end of the sleeve 35 screws the foot-piece 21 locked in place by a jam nut 36. A similar jam nut 37 fastens the upper end of the sleeve 35 in position on the lower leg 32. By the arrangement described, the lower leg can be lengthened or shortened on correspondingly screwing the sleeve 35 in the lower leg 32 and adjusting the foot 21 on the sleeve 35. It will be noticed that by providing articulated legs and pivotally connecting the legs with the body the diver is enabled to easily move the legs. It will also be noticed that the joints are waterproof and hence water is not liable to leak into the diver's suit especially as the oil is used in the joints 15 and 30 to prevent leakage of the water into the suit.

The body 10 is provided at the sides with tubular joints 40 for the arms 41 to swing forwardly and backwardly. Each of the arms comprises a shoulder 42 in the form of an elbow, an upper arm 43 and a lower

105

110

forearm 44 closed at its end by a cap 45. The elbow 42 is provided with a flange 50 fitting into an annular groove 51 formed in the joint 40 to allow the elbow to swing forward 5 and backward, the flange 50 being engaged by a retaining ring 52 fastened in place on the joint 40 by screws 53 which also serve to fasten the joint 40 to the body 10.

On the lower end of the shoulder 42 screws 10 a joint 60 engaged by a flange 61 formed on the upper end of the upper arm 43 and held in place by a retaining ring 62. The lower end of the upper arm 43 is provided with an angular joint 65 engaged by a flange 66 on 15 the upper end of the forearm 44, and the said flange 66 is held in place by a retaining ring 67 screwing on the lower end of the upper arm 43. It will be noticed that the connection between the upper arm 43 and 20 the shoulder 42 permits turning of the upper arm and by connecting the forearm 44 with the upper arm 43 by the connection described the forearm may be swung outward and upward or downward and inward.

25 The bottom of the cap 45 is provided with an annular groove 70 in which is mounted to turn a flange 71 extending upwardly from a crosspiece 75 provided with a stem 73 extending upwardly through the bottom of the 30 cap 45 into the lower end of the arm 41. The upper end of the stem 73 is provided with a handle 74 adapted to be taken hold of by the hand of the diver in the corresponding arm 41. The crosspiece 75 is pivotally connected by links 76 with gripping jaws 77 pivotally connected with each other by links 78. The flange 71 is held in place by a retaining cap 79 screwing on the cap 45. A plug 80 is arranged in the bottom of 40 the cap 45 to fill the groove 70 with oil. Now by the diver having hold of the handle 74 the latter can be turned so as to swing the gripping jaws 77 toward or from each other. In swinging the gripping jaws 77 45 from each other into open position they can be readily engaged with an object, and on turning the handle in the opposite direction the gripping jaws 77 are moved into closed

position thus gripping the object. From the foregoing it will be seen that the diver can 50 readily manipulate the gripping jaws 77 from inside of the arm 41 thereby enabling the diver to do submarine work.

In order to lower or raise the diver a cable or other lowering or hoisting means 90 55 is connected exteriorly with the body 10, and in order to supply the diver with fresh air use is made of a hose 91 connected with the body 10 and fastened to an air pump for pumping fresh air into the diver's suit. 60

Having thus described my invention, I claim as new and desire to secure by Letters Patent:—

1. A diver's suit of a non-flexible pressure resisting material having members connected with each other by a leak-proof joint, the joint comprising two parts, of which one part is provided with a recess containing a liquid and the other part is provided with a flange fitting into the said recess with its 65 end spaced from the bottom of the recess and bearing against the said liquid.

2. A diver's suit of non-flexible pressure resisting material having members connected with each other by a joint, the joint comprising two parts, of which one is provided with an annular recess containing a liquid, and the other part is provided with an annular flange fitting into the said recess and bearing against the said liquid, the said 75 flange having inner and outer packing rings, and means holding the said flange part in position on the said recessed part and the said parts on the body.

3. In a diver's suit, a body, a limb, and a 85 joint for connecting the limb thereto, said joint consisting of a flanged member having an annular recess containing a liquid, a flange on the member and fitting in the recess with its end spaced from the bottom of the recess and bearing on the liquid, a retaining ring engaging the flanges of the limb and member, and bolts passing through the ring and flange of the member into the 90 body.

VICTOR CAMPOS.
